UNITED STATES PATENT OFFICE.

CHARLES S. BATDORF, OF BROOKLYN, NEW YORK.

COIN-SORTER.

SPECIFICATION forming part of Letters Patent No. 748,836, dated January 5, 1904.

Application filed September 22, 1903. Serial No. 174,154. (No model.)

To all whom it may concern:

Be it known that I, CHARLES S. BATDORF, a citizen of the United States, residing at Brooklyn, in the county of Kings and State of New York, have invented new and useful Improvements in Coin-Sorters, of which the following is a specification.

My invention relates to certain new and useful means for sorting coins; and the object of the invention is to provide a convenient means for rapidly and accurately assorting various denominations of silver and other coin, so as to facilitate the counting thereof in banks, counting-houses, and other places where large quantities of mixed coin are handled, and to supply the requirements of coin-counting machines such as I have shown, described, and claimed in my former patent, No. 691,435, dated January 21, 1902, and in a later application for patent for certain improvements thereon filed March 12, 1903, Serial No. 147,459.

To this end my invention comprehends a cabinet or coin-receptacle and a vertical series of trays, each of which, except the lower one, is formed with a bottom that is provided with closely-set rows of circular openings that communicate with the trays beneath, the openings in the bottom of each tray being smaller than those in the bottom of the next tray above, whereby the larger coins are retained in the upper tray or trays, while the smaller coins will pass successively through the several trays to the bottom. The receptacle is provided with a suitable cover with an opening to admit the coins to the uppermost tray, said cover provided with means for locking it in place during the agitation of the receptacle to effect the separation of the coins, and the trays are so arranged that the bottom of one rests directly upon the top of the one next below to prevent a coin lodging between the trays, and each tray will be provided with overhanging flanges at the top edge to serve as a handhold in removing loaded trays and replacing empty ones. Coins of various denominations and sizes when mixed promiscuously may thus be rapidly and accurately separated for counting, there by effecting a considerable saving in the time and labor ordinarily expended in sorting and counting large quantities of coin.

In the accompanying drawings, forming part of this specification, and in which similar letters of reference indicate like parts throughout the several views, Figure 1 is a perspective view of a coin-sorting device embodying my invention. Fig. 2 is a side elevation of the same, partly broken away. Fig. 3 is a perspective view of one of the trays removed.

In the said drawings, A represents a base made of any appropriate material and of such size and shape as may be found most suitable for the objects in view. In the drawings the base is shown approximately square, as this form is well suited for my purpose, although I do not limit myself to this form.

At the four corners of the base shown are the uprights or corner-posts B, which I prefer to make of light angle-iron or like material, with the flanges presented inwardly to form vertical guides for the trays to be hereinafter described. The base member A is formed or provided at the corners with angle brackets or projections C, and into these the lower ends of the angle-iron uprights or posts fit and are secured by screws or other fastening means. At the upper ends of the uprights or corner-posts there are similar angle brackets or projections D, into which the upper ends of the uprights are fitted and secured in the manner described for the lower brackets C, said upper brackets at one side of the device being also formed or provided with lugs a, forming members of the hinges of a suitable cover D', which has lugs or eyes b, coinciding with the lugs or eyes a, to form the hinges of the cover, said lugs or eyes a b being engaged by an appropriate pintle c. The upper corner-brackets are rigid with connecting-bars e, which form a rigid member or connection between the uprights or corner-posts at the top, and on top of these bars and the upper corner-brackets the cover D' closes, said cover having a central opening through which the coins are introduced and a pivoted or other latch member F, which is adapted to swing down over the front edge of the device to temporarily secure the cover during the assorting operation. In addition to the foregoing the rigid framework formed by the top and bottom

portions and the uprights or corner-posts is provided with appropriate handles G, which may be grasped to shake the device to effect the separation of the coins and the deposit 5 of said coins in their respective trays.

The trays H preferably follow the general shape of the interior of the rigid exterior frame, and their exterior diameter is such that they occupy the horizontal space between the uprights or corner-posts, their angles fitting the said angle-iron uprights and being guided thereby when the trays are removed from or replaced in the frame. In the drawings I show five (5) trays for containing coins of the denomination of fifty (50) cents, twenty-five (25) cents, five (5) cents, pennies, and dimes, respectively, and said trays substantially fill the space between the cover and the bottom of the device, and the bottom of one tray above the lowermost one rests directly upon the top edge of the tray next below it, so as to prevent a coin finding lodgment between the edges of the trays. With the exception of the lowermost tray, whose bottom is closed, the other trays have perforated bottoms adapted to retain coins of a certain diameter and permit all smaller coins to pass through to the tray beneath, thus separating or assorting the various-sized coins that are introduced through the cover-opening into the uppermost tray. Each tray has, preferably, an inturned horizontal flange g at the top of opposite sides to form handles to facilitate the removal and replacing of the trays. It will be understood, of course, that the openings in any one tray are all of one size or diameter and that the sizes of the openings in the respective trays are so graded or arranged as to obstruct the passage of coins of a larger diameter, while permitting coins of a smaller diameter to pass through to the next lower tray, and so on. Thus in a cabinet arranged for assorting silver coin of all the various denominations the top tray will be provided with circular openings sufficiently large to permit the passage of all silver coins except dollars. The next tray below will have openings to permit the passage of all silver coins except half-dollars, and so on to the bottom, in which the small coins—say dimes—only are received. This bottom tray, therefore, does not require a perforated bottom.

From the foregoing the manner of using my coin-sorter will be apparent. After a proper set of trays have been placed in position the mixed coin is thrown into the top tray through the opening in the cover. By now shaking the cabinet so as to agitate the coin in the top tray all the small coin will pass successively into and through the next lower tray or trays to the bottom one, the various denominations being thus rapidly assorted, so that, for instance, the top tray will contain only silver dollars, the next tray half-dollars, the next tray below quarter-dollars, and so on to the bottom tray if more than

three are employed, the last or lower tray containing only the smaller coin—say dimes. The same principle can also be applied in a cabinet arranged for sorting gold coin.

Having thus described my invention, what I claim as my invention is—

1. In a coin - sorter the combination of a rigid framework comprising top and bottom members and uprights or corner-posts, said posts having vertical guides in their inner sides and said top member having a tray-admission opening, and removable trays inserted through the top member of the framework and being guided to their positions by said uprights or corner-posts.

2. In a coin-sorter, the combination of a rigid open framework including top and bottom members and angle-iron uprights forming corner-posts, and trays fitting within said frame and introduced and removed vertically through the top member of the frame, the channels of the said uprights forming vertical guides for the trays, and said trays having perforated bottoms graded to assort coins of different denominations and arranged one above the other within the frame.

3. In a coin-sorter, the combination of a frame or casing including a base and a top section each provided with angular corner-brackets, angle-iron uprights fitting and extending between the corner - brackets and forming corner-posts for the frame or casing, trays of a diameter substantially equal to the distance between opposite uprights or corner-posts said trays inserted and removed vertically through the top section of the frame or casing and having their angles vertically guided in the angles of the uprights, and a top closure for the frame or casing said trays having perforated bottoms graded to assort coins of different denominations and arranged one above the other.

4. In a coin-sorter the combination of a casing composed of a bottom plate with upwardly-projecting angle-brackets at the corners, a top member having downwardly-extending angle-brackets at the corners, angle-iron corner-posts fitting and connecting the angle-brackets of the bottom plate and top member, trays insertible in the casing through the top member thereof and having their corners guided by the corner-posts, said trays having perforated bottoms graded to assort coins of different denominations, and a cover hinged at one side of the frame or casing and closable over the top member thereof and provided with means for securing the cover in a closed position, said cover having an opening to admit the coins to the uppermost tray and said frame or casing having handles by which it may be agitated.

5. In a coin-sorter, the combination with a framework or casing open at the top and provided with vertical guides at the corners, a series of trays having their angles fitting said guides said trays insertible and removable through said open top of the casing and rest-

ing one upon the other, and having perforated bottoms graded to assort coins of different denominations, said trays having flanges along the top of opposite sides to serve as handholds for removing and replacing the trays, and a closure for the uppermost tray.

In testimony whereof I have hereunto set

my hand in presence of two subscribing witnesses.

CHARLES S. BATDORF.
